UNITED STATES PATENT OFFICE.

WILLIAM WILSON SCOTT, OF MONTREAL, QUEBEC, CANADA.

FLOOR-PLANING TOOL.

No. 898,793.

Specification of Letters Patent. Patented Sept. 15, 1908.

Application filed July 28, 1906. Serial No. 328,257.

To all whom it may concern:

Be it known that I, WILLIAM WILSON SCOTT, of the city of Montreal, Province of Quebec, Canada, have invented certain new and useful Improvements in Floor-Planing Tools; and I do hereby declare that the following is a full, clear, and exact description of the same.

My invention relates particularly to floor planing machines and it has for its object to provide a machine of this type adapted to be moved over the floor and plane the surface thereof.

The invention may be said briefly to consist of a carriage adapted to skid along the surface of the floor and having a rotary knife mounted thereon and means for varying the extent to which the knife cuts into the surface of the floor such rotary knife consisting of a rotary device having a series of blades mounted thereon while such blades act upon the surface of the floor through an opening in the frame of the machine.

For full comprehension, however, of my invention reference must be had to accompanying drawings forming a part of this specification in which similar reference characters indicate the same parts and wherein

Figure 1, is a side elevation of a floor planing machine constructed according to my invention, Fig. 2, is a plan view thereof, Fig. 3, is a front elevation, Fig. 4, is a transverse vertical sectional view of the base plate alone taken on line $z-z$ Fig. 2.

My improved planing tool consists of a plate b adapted to be slid along the floor by a pair of handles c d the former of which is bolted as at e to the rear of the plate and the latter is threaded into a socket g preferably formed in one with such plate and preferably located at the front thereof.

In the preferred embodiment of my invention bearings h h are located near the front of the plate one at each side thereof and an adjustable plate i is fulcrumed at its forward end upon a spindle j supported in such bearings. A pillow block k is bolted to the top of this carrying plate and has a bearing l at its upper end in which is supported a driving shaft n upon one end of which is mounted the rotary part indicated by dotted lines at p while a driving pinion m is mounted rigidly upon the opposite end thereof. A cylinder r carried by this pillow block incloses the rotary part p and has a motive fluid intake duct s to which is connected a flexible tubular con-

ductor t leading from any available source (not shown). The pillow block also affords a bearing for a driven shaft u and a counter shaft v intermediate such driving and driven shafts between which an operative connection is established by a train of gears 2 3 and 4 the two first of which (2 and 3) are mounted upon the counter shaft v and the first mentioned intermeshing with the driving pinion m while the last mentioned gear (3) intermeshes with the gear 4 which is mounted upon the driven shaft u . This driven shaft has its free end squared as at 5 to receive the rotary cutter. This rotary cutter preferably consists of a square carrying member, 10, secured rigidly upon the square end of the driven shaft, u , by a nut, 11, screwed upon the end of such driven shaft which is diminished and screw-threaded for the purpose. A series of flat blades, 12, are bolted to the sides of this square carrying member through slots, 13, therein, which allow such blades to be adjusted relatively to the edges of the carrying member which they overlap.

An adjusting screw, 15, is carried by the carrying plate and projects downwardly therethrough into bearing relation with the top of the base plate, the function thereof being to limit the extent to which the cutting edges will project below the base plate, while a lock-nut 16 upon the adjusting screw sets the latter against accidental displacement. A lever fulcrumed adjacent to the top of the rear handle is connected by a rod, 17, to the rear end of the carrying plate, as at 18, the purpose thereof being to enable the cutter to be lifted out of engagement with the floor when it is desired to move the machine without the cutter being in operation.

If desired the device can be utilized for doing bench work the rotary cutter being removed and a circular saw as indicated at 60 substituted therefor while the base plate will be clamped at one end of the bench.

What I claim is as follows:

1. A floor planing tool consisting of a base plate adapted to be slid upon the floor and having an opening therein, a plate located above such base plate and pivoted at one end thereto, a rotary cutter supported upon the adjustable plate in position to have the cutting portion thereof project through the opening in such base plate, a pair of handle-bars projecting upwardly from the base plate, 105 a bell crank lever fulcrumed to one of the handle bars near the handle portion thereof,

a link connecting such bell crank lever to the adjustable plate, and means whereby the rotary cutter is driven.

2. A floor planing tool consisting of a base plate adapted to be slid upon the floor and having an opening therein, a plate located above such base plate and pivoted at one end thereto, a rotary cutter supported upon the adjustable plate in position to have the cutting portion thereof project through the opening in such base plate, a pair of handle-bars projecting upwardly from the base plate, a bell crank lever fulcrumed to one of the handle bars near the handle portion thereof, a link connecting such bell crank lever to the adjustable plate, means for adjusting the normal position of the pivoted plate relatively to the base plate and means whereby the rotary cutter is driven.
2. 3. A floor planing tool comprising a base plate having an opening, a plate pivoted at one end to the base plate and carrying a transverse shaft; a rotary cutter mounted

upon one end of such shaft and a gear upon the opposite end thereof the cutter being in 25 juxtaposition with the opening in the base plate and adapted to be projected therethrough; a counter shaft carried by such pivoted plate; a gear mounted upon one end of the counter shaft and intermeshing with the 30 first mentioned gear, and a motor upon the opposite end of such counter shaft; a pair of handle bars carried by opposite ends of the base plate; a bell crank lever mounted near the top of one of such handle bars and a link 35 connecting such bell-crank-lever to the free end of the pivoted plate; and a set screw carried by the said pivoted plate and bearing upon the base plate, for the purpose set forth.

In testimony whereof, I have signed my 40 name to this specification, in the presence of two subscribing witnesses.

WILLIAM WILSON SCOTT.
